UNITED STATES PATENT OFFICE.

WILLIAM EDWARD HEADLEY, JR., OF MISSOULA, MONTANA.

SIGNALING DEVICE.

1,242,690.

Specification of Letters Patent.

Patented Oct. 9, 1917.

Application filed June 1, 1915. Serial No. 31,408.

To all whom it may concern:

Be it known that I, WILLIAM E. HEADLEY, Jr., a citizen of the United States, and a resident of Missoula, in the county of Missoula and State of Montana, have invented certain new and useful Improvements in Signaling Devices, of which the following is a specification.

My invention is an improvement in signaling devices, especially adapted for use with automobiles, for indicating the intentions of the driver, with regard to turning and the direction of turning, stopping and the like, wherein signal mechanism is arranged, preferably at the front of the vehicle, and in a conspicuous position, the said mechanism being arranged to be electrically operated by the driver, and by the turning of the wheel.

20. In the drawings,

Figure 1 is a perspective view of a portion of an automobile provided with the improvement;

Fig. 2 is an enlarged section on the line 2—2 of Fig. 1, looking in the direction of the arrow adjacent to the line;

Fig. 3 is a diagrammatic view of the wiring;

Fig. 4 is an end view of the signal casing with the cover plate removed;

Fig. 5 is a section on the line 5—5 of Fig. 2;

Fig. 6 is a front view of the signal casing with parts broken away;

35 Fig. 7 is a section on the line 7—7 of Fig. 5, looking in the direction of the arrow adjacent to the line;

Fig. 8 is a plan view of the reflector.

Fig. 9 is an enlarged section on the line 40 9—9 of Fig. 7;

Fig. 10 is an enlarged partial front view of the automobile showing the mounting of the casing;

Fig. 11 is a side view of Fig. 10;

45 Fig. 12 is a section on the line 12—12 of Fig. 10;

Fig. 13 is a section on the line 13—13 of Fig. 12; and

Fig. 14 is a section on the line 14—14 of 50 Fig. 13, Figs. 12, 13 and 14 looking in the directions of the arrows adjacent to the respective lines.

The present embodiment of the invention is shown in connection with an automobile, 55 the casing containing the signaling mechanism being arranged above the top of the

vehicle 1. The signal casing, which comprises a body 2 and heads 3, is supported by rods or pipes 4, each rod having one end received in a central hub or sleeve 5 connected 60 with the adjacent head of the casing, and secured thereto by means of set screws 6 or the like. The other end of each rod is bent at an angle as shown at 7, and is connected with a tubular hinge consisting of a section 65 or leaf 8 and a section or leaf 8^a. The section 8 of the hinge is pivotally connected to the section 8^a, as shown more particularly in Fig. 14, by means of a substantially cup-shaped bearing 9. This bearing has a central opening through which the section 8 of the hinge extends and within the bearing the section or leaf is flanged upwardly, as shown at 10, to prevent disengagement of 70 the section or leaf, while permitting it to rotate freely with respect to the bearing.

The bearing 9 at its open end partially embraces the adjacent end of the section 8^a of the hinge, the said section or leaf having a head 11 of cylindrical form within the 80 bearing, and screws 12 are passed radially through the bearing and into engagement with the head, to connect the parts together. An arc-shaped bearing plate 13 is arranged above the leaf and outside of the head, and 85 screws 14 are passed through the bearing plate into engagement with the head.

A tubular rod or pipe 15 is connected with the lower end of the section 8^a of the hinge, and the lower end of each of the pipes or 90 rods 15 is connected to one of the leaves or sections 16 of a hinge similar to the hinge 8—8^a, and comprising the leaf 16 and a leaf 16^a. The leaves 16 and 16^a are connected by a bearing 17 corresponding with the bearing 9, and said hinge is tubular and similar in 95 all respects to the hinge 8—8^a, and for this reason is not further described.

Each hinge leaf 16^a is connected to the upper end of a bracket arm 18, also tubular, 100 and having its lower end connected to the adjacent end of the wind shield 19 of the vehicle. The bearing 9 before mentioned, is at one end of an arc-shaped bar 20, and the bearing 17 is at one end of an arm 21. The 105 arc-shaped bar 20 has a longitudinal slot 22, extending from near the bearing to near the other end of the bar, and the arm 21 has at the opposite end from the bearing 17 an opening which registers with the slot 22 of 110 the bar 20.

A set screw 23 is passed through the slot

and the opening from within outward, and the outer end of the set screw is engaged by a wing nut 24. It will be evident that when the wing nuts at the opposite sides of the vehicle are loosened, the signal casing and its supporting mechanism may swing rearwardly and downwardly, as indicated in dotted lines in Fig. 11. The rods or uprights 15 will swing as indicated in dotted lines in the said figure, until the signal casing is directly behind the upper portion of the wind shield. The arc-shaped bars 20 move with the signal casing, and when the signal casing is in its lowermost position, the set screws 23 will engage the upper ends of the slots 22 of the arc-shaped bars 20. By means of the set screws 23 and the nuts 24, the signal casing may be held in any desired position.

It will be noted from an inspection of Fig. 13, that the ends of the tubular rods or pipes 4 and 15 are threaded into the adjacent ends of the hinge leaves 8 and 8^a, and the ends of the pipe or rod 15, and the bracket 18 are similarly engaged with the leaves of the hinge 16—16^a.

The body of the signal casing is closed at each end by a disk-shaped head 25, and the heads 3, which are approximately conical, are outside of the heads 25. The heads 25 are held in place by screws 26 which are passed radially inward through the body into engagement with a marginal inwardly extending rib on the adjacent head 25, and the large ends of the heads 3 fit against the outer faces of the disk or heads 25. These heads 3 are held in place by means of the set screws 6 before mentioned.

Each of the heads 25 has a central hub 27 fitting over the adjacent tubular rod or pipe 4, and the said pipes extend through the heads 25, and through central hubs 28 in other heads 29 arranged within the body of the casing. Each of the heads 29 has an inwardly extending continuous rib or flange 30 near its periphery. The ribs 30 are of hexagonal form, and the arrangement of the ribs on the heads corresponds, so that each section of each rib registers with a similar section on the rib of the other head.

Six sheets 31 of glass are arranged between the heads, each sheet being of a length to extend from the inner surface of one head to the inner surface of the other head, and the six sheets of glass entirely inclose the space between the heads. As shown more particularly in Fig. 9, a strip 32 of packing or the like is arranged between each sheet and the adjacent portion of the rib, and the sheets are held in place by representations 33 of arrows.

Each of these representations 33 is of sheet metal, cut or stamped to shape, and provided at its ends with angular flanges 34.

The flanges 34 abut against the inner faces

of the disks or heads 29 and are secured thereto by means of screws 35. Preferably, each of the screws 35 is provided with a nut lock 36 to prevent disengagement thereof.

Sundry of the sheets of glass are colored, two sheets being colored red, two green, and the remaining two being of white glass. The similarly colored sheets are oppositely arranged, the white being directly opposite, as shown, and the white sheets have no representations or signals, the said representations or signals being confined to the red and green sheets. The white sheets are held in place by angular clips 37, each consisting of a portion fitting the inner face of the disk or head, and the screws 35 are passed through these last named portions to secure them to the heads. It will be noticed from an inspection of Fig. 5, that the representations 33 are oppositely arranged, those of the green glass pointing in the opposite direction to those of the red glass.

Illuminating mechanism is arranged within the casing formed by the heads 29 and the sheets 31 of glass. This illuminating mechanism consists of two incandescent bulbs 38, which are held within the said casing by a support connected to the inner ends of the tubular rods or pipes 4. The said support comprises a yoke-shaped member 39 consisting of a body 39 and arms 40, and each arm has a central internally threaded hub 41, into which the inner end of the adjacent rod 4 is threaded. The upper ends of the arms are connected by a cross bar 42, the said bar being connected to the arms by means of screws 43.

The sockets 44 for the bulbs are secured to the upper face of the body 39 of the yoke-shaped member, and the bulbs are arranged in inverted position, as shown. Four reflectors are connected with the arms of the support, a reflector being arranged above and below the bulb, and one at each end of the same. Of these reflectors, as shown more particularly in Fig. 8, the upper and lower are alike, and the end reflectors are alike. The upper and lower reflectors each consists of two portions 45 and 45^a extending at an obtuse angle with respect to each other, and each of the end reflectors consists of two portions 46 and 46^a, also extending at an obtuse angle. All of the reflectors are arranged with the angle between the two portions inward, and the upper and lower reflectors are supported by the end reflectors. The ends of all of the reflectors are mitered to fit, as shown more particularly in Fig. 5, and the entire reflector is supported by angle plates 47, each consisting of two portions extending at an acute angle with respect to each other.

The angle plates are arranged in pairs, one of the pairs being at each end of the reflecting system, and each angle plate has one

of its portions secured to the adjacent portion of the adjacent end reflector, while the other portion is lapped upon the adjacent side of the adjacent arm, 40 of the support. 5 Screws 48 or the like are passed through the said last named portions into engagement with the arms, and the system is so arranged that the bulbs are at the center of the system.

10 Eye bolts 49 are connected to the outer faces of the end reflectors, the eye bolts being arranged in pairs, and one pair being connected to each reflector. The eye bolts are connected to the respective portions of 15 the end reflectors, each eye bolt being connected to a pin 50 on the reflector. The eye bolts extend upwardly at the ends of the respective portions of the upper reflector.

15 The illuminating apparatus is supplied 20 with current from a suitable source of electrical energy interposed in a circuit consisting of lead wires 54 and 55. As shown, the bulbs are arranged in parallel in the circuit, and from the bulbs lead wires extend 25 through the tubular rod 4 at the left of Fig. 5, and pass to the source of energy by way of said rod, and the rods or pipes 15 and 18, the wires passing through the hinges 8-8^a and 16-16^a and entering the adjacent 30 rod or pipe 4.

Between the heads 3 and 25 the said pipe or rod is provided with a lateral or radial opening 56, and a lead wire 54 extends through the said opening into the space between the heads 3 and 25 and is connected to a binding post 57 connected to the head 25, and insulated therefrom as shown, by an insulating sleeve. Other binding posts 58 and 59 are connected with the said head 40 at opposite sides of the post 57, and at opposite sides of the rod 4, and each of the said posts is insulated from the head in the same manner as the post 57.

Lead wires 60 and 61 are connected with 45 the posts 58 and 59, and the said wires pass inwardly through the opening 56 into the bore of the pipe or rod. These wires pass from the pipe or rod 4 at the right of Figs. 1 and 5, through the adjacent hinge 8-8^a, the pipe or rod 15, and the hinge 16-16^a to the bracket 18, finally emerging from the said bracket at the lower end thereof.

50 Referring to Fig. 1, it will be noticed that push buttons 62 and 63 are arranged on the steering wheel, at opposite sides thereof. A pair of solenoids is mounted on the head 25 at the right of Fig. 5. One of the solenoids 64 has one terminal connected with the binding post 58, and one of the terminals of the other solenoid 65 is connected to the binding post 59. A wire 66 connects the binding post 57 with the other terminals 60 of the solenoids, the said wire branching as shown, for the connection.

65 These solenoids are designed for coöpera-

tion with a radial arm 67 having a hub 68 which encircles a sleeve 69 on the adjacent rod 4, and the hub is secured to the sleeve by a set screw, as shown. This arm 67 is provided at its outer end with an arc-shaped opening through which extends an arc-shaped core 70, and the said core is held in adjusted position by means of a set screw 71 passing through the end of the arm into engagement with the core. The core coöperates with both solenoids, as will be evident from an inspection of Fig. 2. When the solenoid 64 is energized the adjacent end of the core will move within the solenoid, swinging the arm 67 toward the solenoid 64. 75 When the solenoid 65 is energized, the arm 67 will be moved in the opposite direction. The solenoids are supported by lugs 72 at their ends, the said lugs being secured to the adjacent head 25 by means of screws, as 80 shown.

85 Stops 73 in the form of angle plates are arranged on the head 25, for limiting the movement of the arm, in either direction. Each stop has a threaded stem 74 which passes 90 through an arc-shaped opening 75 in the head, and each stem is engaged by a nut 76 on the opposite side of the head for holding the stop in adjusted position. The arm and the core 70 are normally held in central position by means of coiled springs 77. These springs at their upper ends are connected with a lug 78 extending inwardly from the head 25, and they diverge at their lower ends, each spring being connected at its 95 lower end to a radial arm 79 on a collar 80 on the sleeve 69. That end of the sleeve 69 adjacent to the head or disk 29 is provided with clutch teeth 87, which are designed to engage similar teeth on the adjacent end of 100 the hub 28 of the said disk 29.

105 The arms 79 extend in opposite directions, and the collar is held to the sleeve by set screws 81. The lug has a base 82 which is secured to the inner face of the head 25 by 110 set screws 83, and the said lug has an arc-shaped opening 84, through which is passed an arc-shaped bar 85, the said bar being of circular cross section, as shown, and the bar is held in adjusted position by means of a 115 set screw 86. The bar 85 extends at its outer ends into the solenoids, and the said solenoids are curved or arc-shaped. This bar might also limit the movement of the core 70, in its movement in either direction. 120

125 The wiring or circuit for operating the improved signal is shown in Fig. 3. In this view, the casing shown diagrammatically at 88, contains the bulbs 38 which are supplied with current by the lead wires 54 and 55. The wire 54 extends to a connection with a lead wire 89, which is connected at one end with one of the terminals of a battery 90 or other suitable source of electrical energy. From the said terminal the lead wire 89 130

passes to a connection with a contact plate or member 91, arranged at one side of the steering wheel, of arc-shape, as shown.

The push button 63 on the steering wheel 5 is interposed in the said lead wire, and a branch 92 leads from the said lead wire 89 to another contact member or plate 91^a at the opposite side of the steering wheel. The push button 62 on the steering wheel is interposed in this wire 92. The steering wheel 10 is provided with a switch arm 93, and the said arm is designed to engage beneath the contact members 91 and 91^a when the wheel is swung or oscillated in opposite directions. 15 When the wheel is moved in one direction, the switch arm 93 will contact with the member 91, while when the said wheel is swung in the opposite direction, the switch arm will contact with the plate or member 91^a. 20 The lead wires 60 and 61 before mentioned, are branched onto the wires 92 and 89, respectively, the wire 60 being branched onto the wire 92 between the push button 62 and the contact plate 91^a, and the wire 25 61 is branched onto the lead wire 89 between the push button 63 and the contact plate 91. The binding post 58 is connected to one of the terminals of the solenoid 64 by a lead wire 94, while the binding post 59 30 is connected to the corresponding terminal of the solenoid 65 by a lead wire 95. The lead wire 66 connects the binding post 57 to the adjacent terminals of the solenoid. A cut out switch is arranged in the lead wire 35 55, and the switch arm 93 on the steering wheel is connected to the lead wire 89, by a lead wire 97, and a cut out switch 98 is interposed in this lead wire.

The signalling mechanism may be operated by the turning of the steering wheel. 40 When the driver intends to turn to the right, for instance, he will press the push button 62. The current passes from battery by way of the lead wire 54, to the illuminating apparatus, returning to battery by way of the lead wire 55. It also passes by way of the lead wire 54 to the binding post 57 through the extension of the said lead wire 54. From the binding post 57 the current 45 passes by way of the lead wires 66 to the solenoid 64, returning to battery by way of the lead wires 94, 60, 92 and 89.

The solenoid 64 is energized and the core 50 70 is drawn thereinto, moving the arm 67 in a direction to cause the signal support to display the representation of an arrow which points in the direction toward which the vehicle will turn, that is, to the right.

Should the operator fail to depress the 55 button 62, the signal will still be displayed, for when he turns the steering wheel to the right, the switch arm 93 will contact with the contact member 91^a. The current now 60 passes from battery by way of the lead wire 65 54 to the illuminating apparatus, returning

by way of the lead wire 55. The current also passes by way of the extension of the lead wire 54 to the binding post 57 and from thence by way of the lead wire 66 to the solenoid 64, returning to battery by way of the lead wires 94, 60, 92 and 89.

When the operator intends to turn to the left, he will depress the push button 63. The current now passes by way of the lead wire 54 to the illuminating apparatus, returning by way of the lead wire 55. By way of the extension of the lead wire 54 the current passes to the binding post 57 and from thence by way of the lead wire 66 to the solenoid 65, returning to battery by way of the lead wires 95, 61 and 89.

Should the operator fail to press the button, the contact of the switch plate 93 with the contact member 91^a will display the signals. The current passes from the battery by way of the lead wire 54 to the illuminating apparatus, returning by way of the lead wire 55.

The current also passes by way of the extension of the lead wire 54 to the binding post 57 and from thence by way of the lead wire 66 to the solenoid 65, returning to the battery by way of the lead wires 95, 61, 97 and 89. In either case, the core 70 is drawn into the solenoid 65, moving the arm 67 in a direction to cause the proper signal to be displayed at the opening 2^a of the signal casing.

The adjustable connection between the core and its support permits the position of the core with respect to the support to be varied.

I claim:

1. In a signal for motor vehicles, and in combination with the signaling means, supporting members hingedly connected, signal operating means passing through the supporting members and the hinge connections thereof, an arc-shaped bar projecting from an element of a hinge joint, an arm extending from an element of another hinge joint, and means for securing the bar and arm to hold the signaling means in the required adjusted position.

2. In a signal for motor vehicles, and in combination with signaling means, a horizontal member carrying the signaling means and having an angular end, a vertical member hinged at one end to the angular end of the horizontal member, a bracket member hinged to the opposite end of the vertical member, signaling operating means passing through the several members and their hinge connections, an arc-shaped bar projecting from the hinge at one end of the vertical member, an arm extending from the hinge at the opposite end of the vertical member, and means adjustably connecting the bar and arm to hold the signaling means in required adjusted position.

3. In combination with an automobile having upwardly extending tubular supporting brackets at the ends of the wind shield and extending above the top, a tubular upright hinged to each bracket, a tubular rod hinged to the upper end of each upright and extending inwardly, a signal casing supported by the rods between the uprights, said uprights being mounted to swing with respect to the brackets to bring the signal casing above the wind shield or behind the same, signal mechanism within the casing, controlling means for the said mechanism passing through the tubular rods, uprights, brackets and hinges, and means in connection with the uprights and the brackets for holding the signal casing in adjusted position, said means comprising arc-shaped slotted bars, each bar having a bearing at its upper end in which the hinge between the adjacent rod and upright is journaled, an arm having a bearing in which the hinge between the upright and the bracket is journaled, said arm having an opening registering with the slot of the bar, and a bolt engaging the opening and the slot, and a nut engaging the bolt.
4. In combination with an automobile having upwardly extending tubular supporting brackets at the ends of the wind shield and extending above the top, a tubular support hinged to each bracket, a tubular rod hinged to the upper end of each upright and extending inwardly, a signal casing supported by the rods between the uprights, said uprights being mounted to swing with respect to the brackets to bring the signal casing above the wind shield or behind the same, signal mechanism within the casing, controlling means for the said mechanism passing through the tubular rods, uprights, brackets and hinges, and means in connection with the uprights and brackets for holding the signal casing in adjusted position.
5. A signaling device for automobiles for indicating the direction of turning and comprising a substantially cylindrical casing having an opening in its front, a signal support mounted to rotate in the casing and having transparent panels adapted to register with the opening, opaque signals in connection with sundry of the panels for indicating the direction of turning, and electrically controlled means for rotating the signals and for illuminating the same, the illuminating means being within the support, and the rotating means comprising a pair of arc-shaped solenoids held within the casing, an arc-shaped core having connection with the signal support and arranged between the solenoids and adapted to be moved into the solenoids alternatively, and an electrical circuit having a source of energy and in which the illuminating means and the solenoids are interposed.
6. A signaling device for automobiles for indicating the direction of turning and comprising a substantially cylindrical casing having an opening in its front, a signal support mounted to rotate in the casing and having transparent panels adapted to register with the opening, opaque signals in connection with sundry of the panels for indicating the direction of turning, and electrically controlled means for rotating the signals and for illuminating the same, the illuminating means being within the support, and the rotating means comprising a pair of arc-shaped solenoids held within the casing, an arc-shaped core arranged between the solenoids and adapted to be moved into the solenoids alternatively, a radial arm adjustably connected with the core intermediate the ends thereof, and with the axis of the signal support, for rotating the said support when the arm is moved, and an electrical circuit having a source of energy and in which the illuminating means and the solenoids are interposed.
7. A signaling device for automobiles, comprising a substantially cylindrical casing having an opening, a signal support mounted to oscillate in the opening, said casing having shafts extending axially therefrom, brackets adapted to be connected to the ends of the wind shield, arms extending longitudinally from the ends of the brackets and journaled thereon to swing into vertical or horizontal position, and means in connection with the brackets and the arms for securing the arms in adjusted position, said brackets, arms and shafts being hollow and communicating for the purpose specified.
8. A signaling device for automobiles, comprising a substantially cylindrical casing having an opening, a signal support mounted to oscillate in the opening, said casing having shafts extending axially therefrom, brackets adapted to be connected to the ends of the wind shield, arms extending longitudinally from the ends of the brackets and journaled thereon to swing into vertical or horizontal position, and means in connection with the brackets and the arms for securing the arms in adjusted position.
